UNITED STATES PATENT OFFICE.

THEODORE W. FOSTER, OF PROVIDENCE, RHODE ISLAND, ASSIGNOR TO THEODORE W. FOSTER & BRO. CO., OF PROVIDENCE, RHODE ISLAND, A CORPORATION OF MAINE.

CONTAINER FOR TOILET PREPARATIONS.

Application filed May 24, 1922. Serial No. 563,417.

To all whom it may concern:

Be it known that I, THEODORE W. FOSTER, a citizen of the United States, residing at Providence, in the county of Providence and 5 State of Rhode Island, have invented certain new and useful Improvements in Containers for Toilet Preparations, of which the following is a specification.

This invention relates to a container or 10 holder for toilet preparations such as rouge, salve and the like, which may be in stick, bar, pencil or other convenient form, and the primary object of this invention is to provide such a container with means whereby 15 the contents may be fed forwardly to protect from the end of the tube into position for ready application.

With these and other objects in view, the 20 invention consists of certain novel features of construction, as will be more fully described, and particularly pointed out in the appended claims.

In the accompanying drawings.

Figure 1 is a view showing my improved 25 container or casing with a cap in position thereon.

Figure 2 is a central sectional elevation 30 showing the preparation carrier and the advancing mechanism therefor.

Figure 3 is a detailed view showing the 35 screw-threaded tube which serves as a means for advancing the carrier, the same being shown as partly broken away to show the thread in its inner wall.

Figure 4 is a detailed view of the inner 40 slotted guide tube in which the carrier is mounted.

Figure 5 is a detail of the carrier.

Figure 6 is an enlarged sectional elevation 45 illustrating a portion of the device with the parts assembled and showing the extension formed on the carrier as projecting through the slot in the slotted tube to engage the screw threads in the threaded tube.

With reference to the drawings, 10 designates the outer, tubular shell which is preferably made of metal with its outer edge turned inwardly at 11 and a short distance below its outer end the wall of this tube is 50 rolled outwardly to form an annular rib 12 to provide a stop for the cover 13.

Within this tube is mounted a screw-threaded, tubular casing 14 which is shown in Figure 3 as being formed of thin metal 55 with the helical thread 15 pressed into the

wall of the stock and this casing is fitted snugly within the outer shell 10 to be frictionally held therein against rotation.

Within this threaded tube is positioned 60 an inner tube 16 as shown in Figure 4, the upper end of which is slightly enlarged as at 17 to engage the inturned lip 11 of the outer casing and the side wall of this inner casing is slotted longitudinally at 18 for the purpose presently described.

The lower end of this inner casing is provided with an annular enlargement 19.

Within this inner tube 16, I have mounted 70 a carrier member 20 which is of cup-shape designed to receive the end of the stick, bar or pencil of toilet preparation and this cup-shaped carrier is mounted within the inner slotted tube 16 and is provided with an integral laterally-extending projection 21 which extends through the slot 18 in the slotted tube into engagement with the thread in the inner wall of the threaded member 14, as best shown in Figure 6, and this projection is preferably formed from 75 the side wall of the carrier.

A cap 22 having a skirt 23 extends over 80 this inner tube member 16 to engage the same with a frictional pressure and this cap is provided with a knurled edge 24 adapted to be engaged by the thumb and 85 finger of the operator to rotate the slotted tube 16, whereby the engagement of the projection 21 with the screw thread 15 causes the carrier to move either up or down by the rotation of this cap relative to the casing to either advance or retract the contents of the tube which is seated in the movable carrier and when the device is not in use the cap 13 may be placed over 90 the upper end of the tube which will cover 95 the contents thereof.

This holder is simple and practical in construction and by its use toilet preparations may be readily carried therein and advanced into position ready for use.

The foregoing description is directed 100 solely towards the construction illustrated, but I desire it to be understood that I reserve the privilege of resorting to all the mechanical changes to which the device is susceptible, the invention being defined and limited only by the terms of the appended 105 claims.

I claim:

1. A holder for toilet preparations com- 110

prising a tubular outer shell and a closure member therefor, an intermediate threaded tube non-rotatably mounted within said shell, a tube rotatably mounted with said threaded tube and provided with a longitudinal slot, a preparation carrying socket adjustably mounted in said slotted tube and having an integral projection extending through said slot and engaging the threads 10 in said intermediate tube, and means for rotating said slotted tube relative to said threaded tube whereby said socket is moved axially of said shell.

2. A holder for stick material comprising 15 a tubular outer shell having an inturned outer end, a lining secured in said shell having an internal helical groove therein, a slotted tube rotatably mounted within said

lining with an enlargement at one end having a bearing at said inturned end of said shell and provided near its other end with an enlargement, a preparation carrying socket adjustably mounted in said slotted tube and having an integral projection extending through said slot and engaging said helical groove, a cap having a recess sprung over the last said enlargement to frictionally secure said cap to said slotted tube, said cap being provided with a shoulder for rotative engagement with said shell and providing a means for causing a relative rotation of said tube and shell whereby said socket is moved axially of said shell. 30

In testimony whereof I affix my signature.

THEODORE W. FOSTER.
